(57) **CLAIM**

An ornamental design for a headlamp for vehicle, as shown and described.

DESCRIPTION

FIG. 1 is a front view of a headlamp for vehicle;
FIG. 2 is a rear view thereof;
FIG. 3 is a top plan view thereof;
FIG. 4 is a bottom view thereof;
FIG. 5 is a left side view thereof;
FIG. 6 is a right side view thereof;
FIG. 7 is a perspective view thereof; and,
FIG. 8 is an enlarged partial view thereof.
Lines shown in FIG. 8 indicate surface contour of the headlamp for vehicle, and don't form a part of the claimed design.
